United States Patent Office

Des. 182,198
Patented Feb. 25, 1958

182,198

SEWING STAND

Catharine A. Platt, La Grange, Ill.

Application December 6, 1955, Serial No. 39,178

Term of patent 14 years

(Cl. D3—19)

Fig. 1

Fig. 2

Fig. 3

I claim:

The ornamental design for a sewing stand, substantially as shown.
